UNITED STATES PATENT OFFICE

2,411,387

RAILWAY TRAFFIC CONTROLLING
APPARATUS

Frank T. Pascoe, Carnegie, and Arthur L. Jerome,
Edgewood, Pa., assignors to The Union Switch
& Signal Company, Swissvale, Pa., a corpora-
tion of Pennsylvania

Application December 8, 1944, Serial No. 567,188

17 Claims. (Cl. 246—3)

1

Our invention relates to railway traffic controlling apparatus and particularly to improved circuits for use in centralized traffic control machines for remote control of traffic in track stretches in which traffic may move in either direction.

In Fig. 1 of application for Letters Patent of the United States, Serial No. 501,254 of H. S. Young, filed September 4, 1943, there are shown interlocked circuits at the control office governed by the signal control levers which govern train movements into the opposite ends of a track stretch, so as to prevent interference with train movements in the event of improper manipulation of these levers and to prevent the reversal of the direction of traffic except when the single track stretch is unoccupied and the signals governing entrance of traffic into the stretch are at stop.

An object of our invention is to provide an improved system of the type described which upon operation of the office equipment to permit a change in the direction of traffic promptly cancels the existing block indications.

A further object of our invention is to provide an improved system of the type described which upon operation of the office equipment to permit a change in the direction of traffic prevents response of selected indication relays to indication codes until control codes have been sent to both ends of the stretch to condition the equipment in the field to establish traffic in the direction determined by the office equipment.

Another object of our invention is to provide an improved system of the type described which upon operation of the office equipment to permit a change in the direction of traffic promptly establishes circuits for the starting relays governing transmission of control codes to opposite ends of the stretch to insure that control codes will be transmitted to both ends of the stretch to thereby make certain that the wayside apparatus will prepare the stretch for traffic in the direction determined by the office equipment.

A further object of the invention is to provide an improved system of the type described which operates to maintain the circuits for the starting relays until the wayside apparatus prepares the stretch for traffic in the direction designated by the office equipment and to thereupon interrupt these circuits for the starting relays.

Another object of the invention is to provide improved apparatus of the type described for use where there is an electrically locked switch at an intermediate point in a track stretch.

2

A further object of the invention is to provide apparatus of the type described which operates to prevent improper changes in the designated traffic direction following movement of the switch lock lever.

Another object of the invention is to provide improved apparatus of the type described which is arranged so that the operator's control of the traffic direction relay for a track stretch is certain to be terminated after occupancy of the stretch even though the stretch becomes occupied before block clear indication codes have been sent to the central office.

Other objects of the invention and features 15 of novelty will be apparent from the following description taken in connection with the accompanying drawing.

We shall describe one form of railway traffic 20 controlling apparatus embodying our invention, together with a modification thereof which we may employ, and shall then point out the novel features thereof in claims.

In practicing our invention we provide a 25 master directional relay of the polar stick type for designating the direction of traffic in each track stretch and provide circuits governed by the levers controlling the signals at the entrance ends of the stretch for operating the relay contacts to one position or the other providing the stretch is vacant and the signals are at stop. Contacts of this directional relay control the polarity of the energy supplied to a neutral auxiliary stick relay so that this relay always releases on movement of the contacts of the directional relay. The auxiliary relay when released energizes the block indication relays to 30 cancel the existing indications and prevent registration of new indications, while the auxiliary relay when released energizes a block repeater stick relay which establishes circuits for the starting relays to insure transmission of control codes to both ends of the stretch and also provides a circuit for the directional relay to 35 permit the relay to be operated pending establishment of traffic in the stretch. The auxiliary relay, when released, is picked up upon energization of the starting relays for both ends of the stretch. The stick circuit for the block repeater relay is interrupted on receipt of indication codes from the field stations showing that 40 the wayside apparatus has established traffic in the designated direction or on receipt of an indication code showing that a detector section is occupied, thus showing that a train has entered 45 the stretch. The switch lock lever governs the 50 stretch, The switch lock lever governs the 55 stretch.

block repeater relay and the block indication relays to insure proper operation of the equipment on movement of this lever.

In the drawing,

Fig. 1 shows a portion of a suitable machine located at a control office and including control panels for two field stations located at opposite ends of a single track block, as indicated by the miniature track diagram at the top of the view, and

Figs. 2 and 3 are fragmentary views showing modifications which we may employ.

Similar reference characters refer to similar parts in each of the three views.

In most instances in the drawing the relay contacts are located directly under the winding of the associated relay, but in some cases, in order to simplify the drawing, relay contacts are separated from the relay winding and in these instances the relay with which the contacts are associated is designated by appropriate reference characters placed above the contacts.

The office and the field stations are each provided with a suitable source of direct current, such as a storage battery, not shown, the terminals of which are designated B and C in the drawing.

Referring to the drawing, there is shown in the upper portion of Fig. 1 a diagram of a stretch of single track railway between two passing sidings together with certain of the field circuits employed in connection with this invention, while the lower portion of this figure shows a portion of a suitable machine located at the control office and incorporating this invention.

In the drawing diagrammatic connections are shown between relays at the field stations and indication relays in the office but it should be understood that communication between the field stations and the office is established by a code system which may be of the type shown in Letters Patent of the United States No. 2,229,249, issued January 21, 1941, to L. V. Lewis, or in application for Letters Patent of the United States, Serial No. 496,907, filed July 31, 1943, by A. P. Jackel, and described in Manual 506A of The Union Switch and Signal Company, Swissvale, Pa.

Consideration of the detailed mode of operation of the code communication system is not needed for an understanding of our invention and it is deemed sufficient to point out that a field station is provided at each end of each track stretch to be controlled and that coding units are provided at the office and at each field station and are connected by a pair of line wires, not shown, over which control codes are transmitted at times from the office to a selected field station, while at other times indication codes are transmitted over the same line wires from the different field stations to the office without interference, and that the transmission of each code includes the temporary establishment of a plurality of communication channels, as for example, seven, between the office and a station to position a group of relays.

Each code includes a distinctive code call by means of which a selector relay 1-2S or 3-4S at the office and a similar relay, not shown, at one station only is energized to effect temporary establishment of seven communication channels between the office and the station. The different stations have different code calls, consequently the selector relays for different stations or panels are not energized at the same time, and the same

channels provide communication at different times with all of the stations.

The explanation of this invention requires only four channels employed in the transmission of control codes and five channels employed in the transmission of indication codes, and in order to simplify the disclosure the other channels and related apparatus have not been shown.

The channels employed in the transmission of control codes are designated 2, 4, 5 and 7, and the channels employed in the transmission of indication codes are designated 10, 12, 13, 14 and 15, the numbers employed to designate these channels being the same as are employed to designate the corresponding channels in the above-identified application of H. S. Young.

It is to be understood that the system of our invention is made up of a number of unit portions generally similar to the one shown in the drawing, but, as the invention may be fully understood from one such portion, only one has been illustrated in the drawing.

The equipment at each field station includes a starting relay, not shown, which responds to a change in position of any of the associated indicating relays to provide connection from terminal B of a source of current to the indication channels to effect delivery of indication codes over the line wires during the time that a delivery relay D at the office is energized to thereby position a group of indication relays in accordance with the condition of energization of the indication channels.

The indication relays at the office governed from the field station at the left-hand or west end of the single track stretch include a relay 1TK which controls a lamp in the track diagram of the control machine to indicate the condition of section 1T containing the track switch 1W, the relay 1TK being controlled by the track relay 1TR for the track section; a signal indication relay 2RHK governed by relay 2RRGP which repeats the stop indications of the signals 2RA and 2RB; and a block indication relay 2RBK controlled by the relay 2RBR which in turn is governed by traffic conditions in the single track stretch. The control of the relays 2RBR and 4LBR is shown diagrammatically in the drawing, but these relays may be governed through the wayside signal system, as explained in the above-identified application of H. S. Young, so as to indicate that the block is clear only when the wayside signal apparatus conditions the stretch for traffic in one direction or the other.

The relays at the field station at the right-hand end of the single track stretch function in a similar manner to control indication relays 3TK, 4LBK and 4LHK at the office.

The block indication lamp BKE in the track diagram of the control machine is governed by the relays 2RBK and 4LBK, one of which indicates the condition of a portion of the single track block and the other that of the remainder.

The signal levers 2SIG and 4SIG are the usual levers for the code control of the signal stick relays, not shown, at the field stations at the opposite ends of the single track stretch. The signal levers 2SIG and 4SIG are electrically interlocked with respect to the control of train movements into the intervening single track stretch by the master directional polarized relay 2-4LP, as in the above-identified application of H. S. Young and also in his Letters Patent of the United States No. 2,326,991.

The push buttons 1-2STB and 3-4STB are

the starting buttons for operating the usual code starting relays 1-2ST and 3-4ST by means of which control codes are initiated and the corresponding stations selected. Each starting relay when energized initiates a control code as described in Patent No. 2,229,249 including a code call for energizing a selector relay S for the same panel. Each selector relay when energized releases the associated starting relay and connects terminal B of a local source of energy to selected ones of the control channels in accordance with the positions of the signal levers and of the contacts of the master directional relay 2-4LP, and at the selected station relays are operated in accordance with the condition of energization of each of the control channels.

The equipment is arranged so that when energy is applied to channel 2 and a control code is transmitted to a field station, a traffic directional control relay FS, not shown, is operated to condition the wayside apparatus to make the end of the stretch at which this relay is located an exit or leaving end. Similarly, the equipment is arranged so that, when energy is not applied to channel 2 and a control code is transmitted to a field station, the traffic direction control relay FS, not shown, is operated to condition the wayside apparatus to make the end of the stretch at which this relay is located an entrance end so that the signal at this point may be controlled by the wayside circuits on operation of an associated code controlled signal relay, not shown.

The equipment is also arranged so that, when energy is supplied to the code channel governing a signal control relay as, for example, channel 5 or 7, and a control code is transmitted to a field station, the signal control relay at that station is operated to render the signal subject to the control of the wayside circuits. When energy is not supplied to the code channel governing a signal control relay, and a control code is transmitted to a field station, the signal control relay at that station is operated to keep the signal at stop irrespective of the wayside circuits.

The equipment at the left-hand or west end of the stretch includes a relay controlled over channel 4 and operating as explained in the above-identified application of H. S. Young to at times condition this end of the stretch to be an exit end and to prevent transmission of a block clear indication code by the field station at this location.

The equipment is shown in the condition which it assumes when the track stretch is vacant, the signals 2R and 4L are at stop, and the office equipment conditions the stretch for westbound traffic. As the stretch is vacant, the block indication relays 2RBK and 4LBK and the detector section indication relays 1TK and 3TK are released and the panel lamps BKE, 1TKE and 3TKE are extinguished. As the signals 2R and 4L are at stop, the relays 2RHK and 4LHK are released, while the westbound direction indicator lamp WFE is lighted by energy supplied over normal polar contact 20 of relay 2-4LP and back contact 21 of relay 2-4BKS. As the block detector section and signal indication relays are all released, energy may be supplied over the circuit controlled by these relays to the relay 2-4LP, but as the signal levers 2 and 4 are both in their center positions the circuits for supplying energy to the relay 2-4LP are interrupted.

It is assumed that the traffic direction relays, not shown, at the field stations were previously

operated to condition the wayside apparatus for westbound traffic.

At this time the relay 2-4BKS is released, while relay 2-4LPS is energized by current supplied over its stick circuit including its own contacts 23 and 24, normal contact 25 of relay 2-4LP, winding of relay 2-4LPS from left to right, and normal polar contact 26 of relay 2-4LP, and the contacts of relay 2-4LPS are picked up and do not establish circuits for the relays 2RBK, 4LBK and 2-4BKS.

If it is desired to clear one of the signals 4L, the lever 4SIG is moved to its left-hand position and the starting button 3-4STB is pressed to establish a pick-up circuit for the starting relay 3-4ST and it picks up to establish a stick circuit for itself and to initiate operation of the office coding unit to transmit a control code to the field station at the right-hand end of the stretch. At the time the starting button 3-4STB is depressed, its contact 28 is closed but as relay 2-4BKS is released its contact 29 interrupts the circuit for supplying energy to relay 1-2ST and it remains released and does not cause a control code to be sent to the field station at the left-hand or west end of the stretch.

The control code transmitted as a result of picking up of relay 3-4ST causes a selector relay 3-4S to pick up with the result that terminal B of the battery is connected over normal polar contact 30 of relay 2-4LP, front contact 31 of relay 3-4S and left-hand contact 32 of the lever 4SIG to channel 5 and a control code is transmitted to operate a signal control relay, not shown, and places one of the signals 4L under the control of the wayside circuits, the one of the signals being determined by the position of switch 3W in the well-known manner.

When selector relay 3-4S picks up, its front contact 27 is closed but as contact 33 of relay 2-4LP is in its normal position, the battery is not connected to channel 2 and the control code sent to the field station at the right-hand end of the stretch causes the traffic direction relay 40 at that location to maintain that end of the stretch as an entrance end.

When one of the signals 4L displays a permissive indication, relay 4LRGP releases so that energy is supplied to channel 12 and when this field station sends an indication code to the office the relay 4LHK is picked up and is held by its stick circuit, while on picking up of relay 4LHK its contact 33 interrupts the circuits for energizing relay 2-4LP and thus prevents movement of the contacts of this relay to change the designated traffic direction while one of the signals 4L authorizes entrance of traffic into the stretch.

If a train accepts the signal and enters the stretch, the wayside equipment operates in the usual manner so that the signal is put to stop and an indication is sent to the office to release relay 4LHK, while the track and block relays control the indication codes sent to the office to pick up the block and detector section relays to light the lamps 3TKE, BKE and 1TKE in the track model, and to interrupt the circuits of the relay 2-4LP to prevent a change in the designated traffic direction during occupancy of the stretch. When the stretch is vacated and the signals are at stop, the indication relays are released and extinguish the lamps 3TKE, BKE and 1TKE and establish the circuits of the relay 2-4LP.

When the stretch is vacant and the signals are at stop, the operator may change the designated

traffic direction by moving the levers 2SIG and 4SIG to supply energy to relay 2-4LP. To change the designated traffic direction from westbound to eastbound, the lever 4SIG must be in either its center or its right-hand position and the lever 2SIG is moved to its right-hand position. If at this time the switch lock lever 2WL is in its center position, as shown, energy is supplied over back contact 33 of relay 4LHK, back contact 34 of relay 2RHK, back contact 35 of relay 4LBK, back contact 36 of relay 2RBK, back contact 37 of relay 3TK, back contact 38 of relay 1TK, contacts 40 and 41 of lever 2WL, contact 42 of lever 2SIG in its right-hand position, and contact 43 of lever 4SIG in its right-hand or its center position to the upper winding of relay 2-4LP. The energy supplied to this winding moves the relay contacts from their normal to their reverse position so that contact 20 interrupts the circuit of lamp WFE and establishes 20 the circuit to permit energy to be supplied to lamp EFE.

On movement of the contacts 25 and 26 of relay 2-4LP to their reverse position, there is a reversal in the direction of flow of energy through the winding of relay 2-4LPS and the contacts of this relay release with the result that contact 23 interrupts the relay stick circuit and the relay contacts remain released. On release of relay 2-4LPS its contacts 45 and 46 establish circuits for the relays 2RBK and 4LBK and their contacts pick up while contact 47 of relay 2-4LPS establishes the pick-up circuit for relay 2-4BKSR, this circuit including contact 48 of lever 2WL which is closed only in the center position of this lever. When relay 2-4BKSR picks up, its contact 49 establishes a stick circuit to keep the relay energized until relays 2RBK and 4LBK both release, or one of the relays 1TK or 3TK pick up. In addition, when relay 2-4BKSR picks up, its contact 21 interrupts the circuits controlled by contact 20 of relay 2-4LP for lighting the lamps WFE and EFE, thus preventing lighting of either of these lamps until establishment of the new direction of traffic is completed. When either of the relays 2RBK and 4LBK is picked up, energy is supplied to the lamp BKE and it is lighted. Lighting of lamp BKE at a time when lamps WFE and EFE are both dark provides a distinctive indication of the fact that a change in the designated traffic direction is in process.

In addition, on picking up of relay 2-4BKSR its contact 29 establishes the circuit controlled by starting button 3-4STB for energizing relay 1-2ST and contact 50 of relay 2-4BKSR establishes a circuit controlled by starting button 1-2STB for energizing relay 3-4ST. Accordingly, after picking up of relay 2-4BKSR energy is supplied to the starting relays for the control panels for both ends of the stretch when the starting button for the panel for either end of the stretch is depressed. As pointed out above, on movement of the contacts of relay 2-4LP there is a reversal in the polarity of the energy supplied to relay 2-4LPS and its contacts release promptly while the relay 2-4BKSR picks up immediately upon release of relay 2-4LPS, with the result that the contacts of relay 2-4BKSR are picked up and establish the circuits for the starting relays before the operator can move his hand from a signal lever to a starting button. Consequently, when a starting button is depressed following a change in the designated traffic direction, the starting relays for both

ends of the stretch are certain to be energized and control codes are certain to be transmitted to both ends of the stretch and the wayside equipment is certain to be conditioned for the new direction of traffic.

When relays 2RBK and 4LBK pick up, their contacts 36 and 35 interrupt the circuits for operating relay 2-4LP, but at this time front contact 39 of relay 2-4BKSR is closed and shunts the contacts 36 and 35 of relays 2RBK and 4LBK to thereby enable the relay 2-4LP to be operated to restore the original traffic direction if this is desired.

When the starting relays 1-2ST and 3-4ST are picked up, the office coding unit is caused to transmit control codes to the field stations at the opposite ends of the stretch, while as soon as the office coding unit starts to transmit a control code, energy is supplied to terminal 57, as explained in the above-identified application of A. P. Jackel, with the result that energy is supplied from this terminal over front contact 52 of relay 3-4ST, front contact 53 of relay 1-2ST, front contact 54 of relay 2-4BKSR, front contact 55 of relay 2RBK, front contact 56 of relay 4LBK, contacts 58 and 24 of relay 2-4LPS, reverse polar contact 25 of relay 2-4LP, winding of relay 2-4LPS, and reverse polar contact 26 of relay 2-4LP to terminal C. The energy supplied over this circuit to relay 2-4LPS picks up the relay contacts with the result that contacts 23 and 24 establish for the relay a stick circuit governed by contacts 25 and 26 of relay 2-4LP so that energy of the same polarity is supplied to relay 2-4LPS over its stick circuit as was supplied to the relay over its pick-up circuit. In addition, on picking up of the contacts of relay 2-4LPS contact 24 is disengaged from contact 58 so that the pick-up circuit for relay 2-4LPS is interrupted.

When relay 2-4LPS picks up, its contacts 45 and 46 interrupt the circuits which they control for energizing the relays 2RBK and 4LBK, but these relays are maintained energized by current supplied over their stick circuits until indication codes are received from the field stations, so the lamp BKE remains lighted. In addition, when relay 2-4LPS picks up, its contact 47 interrupts the pick-up circuit for relay 2-4BKSR, but this relay is maintained picked up by energy supplied over its stick circuit which includes back contact 92 of relay 1TK, back contact 93 of relay 3TK, its own front contact 49, and front contacts 60 and 61 of relays 2RBK and 4LBK, and contact 21 of relay 2-4BKSR continues to interrupt the circuits of lamps WFE and EFE, while contacts 29 and 50 maintain the circuits for the starting relays so that depression of either starting button energizes both starting relays.

When the office coding unit operates to transmit a control code to the field station at the left-hand end of the stretch, front contact 64 of relay 1-2S is closed, but as contact 30 of relay 2-4LP is now in its reverse position, energy is not supplied to channel 2 and the control code sent to the field station at the west end of the stretch causes the traffic direction relay at that location to change that end of the stretch from an exit to an entrance end.

At this time energy is supplied over reverse polar contact 30 of relay 2-4LP, front contact 65 of relay 1-2S, and right-hand contact 66 of lever 2SIG to channel 7 so the control code transmitted to the field station at the left-hand end of the stretch operates the signal control relay

at that location to permit clearing of signal 2RA or 2RB.

When the office coding unit operates to transmit a control code to the field station at the right-hand end of the stretch, the relay 3-4S is picked up and energy is supplied over reverse polar contact 30 of relay 2-4LP, and front contact 27 of relay 3-4S to channel 2 so that the traffic direction relay at the east end of the stretch is operated to change that end of the stretch from an entrance to an exit end. At this time, front contact 31 of relay 3-4S is closed but as contact 30 of relay 2-4LP is in its reverse position, energy cannot be supplied to channel 5 and the control code sent at this time causes the signal control relay at this field station to maintain the signals 4LA and 4LB at stop.

As a result of transmission of control codes, the starting relays 1-2ST and 3-4ST are released in the usual manner, and their contacts 53 and 52 interrupt the pick-up circuit for relay 2-4LPS.

The control codes sent to the field stations cause the wayside equipment to prepare the stretch for eastbound traffic while one of the signals 2R clears and causes relay 2RRGP to release. When the wayside equipment operates to establish eastbound traffic indication codes are sent to the office to release relays 2RBK and 4LBK, while release of relay 2RRGP causes an indication code to be sent to the office to pick up relay 2RHK.

On release of relays 2RBK and 4LBK their contacts 60 and 61 interrupt the stick circuit for relay 2-4BKSR and it releases to additionally interrupt its own stick circuit and its contacts 29 and 50 interrupt the circuits governed by the starting buttons for the starting relays at opposite ends of the stretch, while contact 21 of relay 2-4BKSR establishes the circuit including reverse polar contact 20 of relay 2-4LP to light the lamp EFE to indicate that eastbound traffic has been established. On release of relays 2RBK and 4LBK the circuits of lamp BKE are interrupted and this lamp is extinguished.

When relay 2-4BKSR releases, its contact 39 in the circuits of relay 2-4LP is opened and control of the relay 2-4LP is restored to the relays 2RBK and 4LBK. At this time, relay 2RHK is picked up and its contact 34 interrupts the circuits of relay 2-4LP to thereby prevent operation of this relay to change the designated traffic direction. In addition, on release of relays 2-4BKSR, 2RBK and 4LBK their contacts 54, 55 and 56 interrupt the pick-up circuit of relay 2-4LPS.

If an eastbound train now accepts the signal 2R and enters the single track stretch, the signal 2R is put to stop and the track relays of the occupied sections are released and control codes are sent to the office to release relay 2RHK and to pick up relay 1TK so that contact 38 of relay 1TK interrupts the circuits of relay 2-4LP to prevent a change in the designated traffic direction during occupancy of the stretch. As the train advances through the stretch, control codes are sent to the office to pick up relay 2RBK so that its contact 36 interrupts the circuits of relay 2-4LP to prevent a change in the designated traffic direction, while a contact of relay 2RBK establishes a circuit for the lamp BKE. Lighting of this lamp accompanied by lighting of lamp EFE provides a distinctive indication of occupancy of the stretch. On continued movement of the train through the stretch, the block and detector section indication relays operate in the

usual manner to control the circuits of the lamps in the track model on the panel of the control machine, while contacts of these relays interrupt the circuits of the relay 2-4LP to insure that the contacts of this relay remain in their right-hand position and maintain eastbound traffic.

Because of code congestion on the C. T. C. system code line, indication codes from the field stations to the office may be delayed and the eastbound train may enter the stretch before indication codes have been sent to the office to release relays 2RBK and 4LBK, and under these conditions indication codes subsequently sent to the office cause relay 2RBK to remain picked up to maintain the stick circuit for relay 2-4BKSR. If relay 2-4BKSR remains picked up, its contact 39 maintains the connection shunting contacts 35 and 36 of relays 4LBK and 2RBK in the circuits of relay 2-4LP, thereby permitting the operator to disestablish the designated traffic direction with resultant interference with progress of the train present in the stretch. This system is arranged so that contacts of relays 1TK and 3TK are included in the stick circuit of relay 2-4BKSR, and on entrance of an eastbound train into the stretch, an indication code is certain to be transmitted to the office to pick up relay 1TK with the result that its contact 92 interrupts the stick circuit for relay 2-4BKSR and causes it to release if it is not already released. Accordingly, if a train enters the stretch before the block clear indication codes are transmitted to the office to release relay 2-4BKSR, this relay will be released when an indication code is sent to the office reporting occupancy of a detector section, and as relay 2-4BKSR is certain to be released after entrance of a train into the stretch, its contact 39 is certain to interrupt the connection shunting contacts 35 and 36 of relays 4LBK and 2RBK in the circuits of relay 2-4LP and thereby prevent the operator from disturbing the designated traffic direction during occupancy of the stretch.

Furthermore, as relay 2-4BKSR is certain to be released during occupancy of the stretch, its contact 21 is certain to establish the circuit of lamps WFE and EFE so that the appropriate one of these lamps is lighted.

If, while the eastbound train under consideration is present in the stretch, the operator wishes to clear one of the signals 2R to permit a second or following train to enter the stretch, he may do so by moving lever 2SIG to its right-hand position and pressing the starting button 1-2STB 55 to pick up relay 1-2ST to send a control code to the field station at the left-hand end of the stretch. At this time, the battery is connected to control channel 7 over reverse polar contact 30 of relay 2-4LP, front contact 65 of relay 1-2S 60 and right-hand contact 66 of lever 2SIG so the control code transmitted at this time operates the signal control relay to clear one of the signals 2R if traffic conditions are proper.

At this time relay 2-4BKSR is released and 65 its contact 50 interrupts the circuit controlled by starting button 1-2STB so that energy is not supplied to relay 3-4ST when the starting button 1-2STB is depressed. Accordingly, a control code is not transmitted to the field station 70 at the right-hand of the stretch. Since the stretch is already prepared for eastbound traffic, transmission of a control code to the east end of the stretch is unnecessary, and as this system eliminates this control code when it is not required, this system reduces the total number of

control codes transmitted and thereby reduces code congestion on the C. T. C. system code line wires.

If, while the stretch is prepared for eastbound traffic, the operator wishes to prepare it for westbound traffic, he may do so provided the stretch is vacant and the signals 2R are at stop so that the circuits of relay 2-4LP are complete. If lever 4SIG is now moved to its left-hand position and lever 2SIG is in either its center or its left-hand position, energy is supplied over the circuit including back contacts of the various indication relays, contacts 49 and 41 of lever 2WL, contact 68 of lever 4SIG, and contact 69 of lever 2SIG to the lower winding of relay 2-4LP to move the contacts of relay 2-4LP to their left-hand or normal positions. On this movement of the contacts of relay 2-4LP, the contacts 25 and 26 change the polarity of the energy supplied to relay 2-4LPS over its stick circuit and the contacts of relay 2-4LPS release with the result that contacts 23 and 24 of relay 2-4LPS interrupt the relay stick circuit and the relay contacts remain released until the starting relays 1-2ST and 3-4ST are picked up to initiate transmission of control codes to both ends of the stretch as explained above. Also on release of relay 2-4LPS pick-up circuits are established for relays 2RBK, 4LBK and 2-4BKSR and these relays pick up to light lamp BKE, prevent supply of energy to lamp WFE or EFE, and establish the circuits for the starting relays so that both of these relays pick up when either starting button is depressed.

As the contacts of relay 2-4LP are in their left-hand or normal position, energy is supplied over normal contact 30 of relay 2-4LP and front contact 64 of relay 1-2S to channel 2 and the control code sent to the left-hand end of the stretch conditions that end of the stretch to be an exit end. As contact 30 of relay 2-4LP is in its left-hand position, energy is not supplied to channel 2 on picking up of contact 21 of relay 3-4S and the control code sent to the right-hand end of the single track stretch conditions that end of the stretch to be the entrance end.

When transmission of control codes to both ends of the stretch is initiated, energy is supplied to relay 2-4LPS over its pick-up circuit and its contacts pick up to interrupt the relay pick-up circuit, establish the relay stick circuit, and interrupt the pick-up circuits of relays 2-4BKSR, 2RBK and 4LBK, while the equipment otherwise operates as explained above during establishment of eastbound traffic.

This system is arranged to insure that even though the contacts of relay 2-4LP are moved more than once before the direction of traffic is finally determined, the direction of traffic indicated in the office is the same as that which is established by the wayside apparatus in the field.

As pointed out above, when the contacts of relay 2-4LP are moved from one position to the other to change the designated traffic direction as, for example, from westbound to eastbound, the polarity of the energy supplied to the relay 2-4LPS is changed and its contacts release to pick up relays 2-4BKSR, 2RBK and 4LBK. If a starting button is now depressed, the relays 1-2ST and 3-4ST pick up to cause energy to be supplied to relay 2-4LPS over its pick-up circuit and its contacts pick up to interrupt the relay pick-up circuit and establish the relay stick circuit, while as soon as control codes can be transmitted to the field stations at the ends of

the stretch, the wayside equipment operates to prepare the stretch for traffic in the direction determined by the position of the contacts of relay 2-4LP, and here assumed to be eastbound.

- 5 If the operator now decides to restore the original direction of traffic, that is, westbound, and moves lever 2SIG to its center or its left-hand position, and moves lever 4SIG to its left-hand position, energy will be supplied to relay 2-4LP 10 to move its contacts to their left-hand position, and on this movement of the relay contacts, the polarity of the energy supplied to the relay 2-4LPS is changed and the relay contacts release to interrupt the relay stick circuit and establish 15 the pick-up circuits for relays 2-4BKSR, 2RBK and 4LBK to pick up these relays if they have released or to maintain them picked up if they have not become released.

If movement of the contacts of relay 2-4LP

- 20 to their left-hand position occurs prior to transmission of a control code to either end of the stretch, that is, while relays 1-2ST and 3-4ST are both picked up, energy will be supplied to relay 2-4LPS over its pick-up circuit as soon as 25 energy is supplied to terminal 57 of the office coding unit and the contacts of relay 2-4LPS will pick up to interrupt the relay pick-up circuit, establish the relay stick circuit, and interrupt the circuits which it controls for relays 2-4BKSR, 2RBK and 4LBK.

If movement of the contacts of relay 2-4LP to their left-hand position occurs prior to transmission of the control codes to either end of the stretch, the control codes which are transmitted 35 will cause the field station equipment to prepare the stretch for traffic in the direction designated by the relay 2-4LP, that is, westbound traffic, and, as relay 2-4LPS is picked up, the indication codes sent to the office following the control codes 40 will release relays 2RBK, 4LBK and 2-4BKSR to show that traffic has been established in the desired direction.

- If movement of the contacts of relay 2-4LP to their normal position does not occur until after 45 a control code has been sent to either one or both ends of the stretch, one or both of the starting relays will be released and the pick-up circuit for relay 2-4LPS will not be established and the contacts of relay 2-4LPS remain released after release of the relay following the change in the polarity of the energy supplied to the relay as a result of movement of the contacts of relay 2-4LP.

As it is assumed that one or both of the control codes was transmitted prior to movement of the contacts of relay 2-4LP to their left-hand or normal position, the equipment at one or both of the field stations will condition the wayside equipment for eastbound traffic, while indication codes may thereafter be sent to the office to release relay 2RBK and/or 4LBK, before control codes are transmitted to establish traffic in the direction now designated by relay 2-4LP, that is, westbound traffic. This is particularly true if 65 after returning the contacts of relay 2-4LP to their left-hand positions, the operator delays pressing of a starting button and thus delays transmission of control codes for the new direction of traffic.

- 70 However, as just explained, relay 2-4LPS is released so that if an indication code is sent to release relay 2RBK or 4LBK the relay will release momentarily during the picked-up period of the associated delivery relay D, but will there- 75 after be picked up again by energy supplied over

the circuit established by a back contact of relay 2-4LPS. Accordingly, relays 2RBK and 4LBK remain picked up and maintain the circuits of lamp BKE and the stick circuits for relay 2-4BKSR, with the result that relay 2-4BKSR is maintained energized by current supplied over both its pick-up and stick circuits. As relay 2-4BKSR is picked up its contacts 29 and 50 maintain the circuits for the starting relays and if either starting button is depressed, both starting relays will be picked up so that control codes will be sent to both ends of the stretch to condition the stretch for traffic in the direction designated by the relay 2-4LP, that is, westbound traffic.

It will be seen that relay 2-4LPS releases whenever the contacts of relay 2-4LP are moved, and that relay 2-4LPS, when released, remains released until control codes are sent to both ends of the stretch, while the relay 2-4LPS when released prevents release of the block indication relays 2RBK and 4LBK and of the relay 2-4BKSR. This arrangement, therefore, prevents registration of block indication codes unless at the time these codes are received the contacts of relay 2-4LP are still in the position which they occupied at the time that the control codes producing the indication codes were transmitted. This mode of operation prevents indication codes showing that the wayside apparatus is prepared for one direction of traffic being recorded at a time when the office equipment designates the opposite direction of traffic and thereby eliminates any possibility that the direction of traffic reported in the office and that actually established in the field will be out of correspondence.

This mode of operation also causes the relay 2-4BKSR to maintain the circuits for the starting relays to thereby insure that, until traffic is established in the designated direction, control codes will be transmitted to both ends of the stretch when the starting button for either end of the stretch is pressed so that the wayside apparatus will operate promptly and positively to establish traffic in the designated direction regardless of unusual or irregular manipulation of the control machine. If the relay 2-4BKSR did not operate in this manner to maintain the circuits for the starting relays, under some conditions pressing of a starting button would energize only the associated starting relay and cause a control code to be sent only to one end of the stretch with the result that the wayside equipment may not prepare the entire stretch for traffic in the desired direction. Although this condition, if it arises, can readily be corrected by pressing the starting button for the station at the other end of the stretch to cause a control code to be transmitted to that station to thereby cause the wayside equipment to complete preparation of the stretch for traffic in the desired direction, the operator may not be aware of the cause of the difficulty or be familiar with the means for overcoming it, and some delay may be experienced in establishing traffic in the desired direction. Since this system operates to cause relay 2-4BKSR to maintain the circuits for the starting relays until establishment of traffic in the designated traffic direction is complete, it makes operation of the equipment prompt and positive and eliminates delays which might otherwise occur.

This system is also arranged to control the wayside equipment to govern electric switch locks

on hand-throw switches at intermediate points in a track stretch. As shown in the track diagram at the top of Fig. 1 there is a switch 2W in the single track stretch between switches 1W and 3W. This switch is equipped with an electric lock which is controlled by the wayside signal circuits in the manner explained in detail in the above-identified application of H. S. Young. Knowledge of the detailed mode of operation of the wayside signal circuits to control the electric lock for switch 2W is not essential to the understanding of this invention and it is deemed sufficient to point out that this lock may be energized to permit a train on the siding to enter the main track when and only when energy is supplied from opposite ends of the stretch to line or other control relays associated with the switch 2W. In order to effect this simultaneous supply of energy from both ends of the stretch it is necessary to condition both ends of the stretch to be exit ends and for the stretch to be unoccupied.

In order to cause the C. T. C. equipment to transmit control codes which will condition both ends of the stretch to be exit ends it is necessary to supply energy to channel 2, or to another channel, such as channel 4, during transmission of control codes to the field stations at the ends of the stretch.

As shown in Fig. 1, the contacts of the relay 2-4LP are in their left-hand positions to designate west-bound traffic for the stretch, the signal levers 2SIG and 4SIG are both in their center positions, the signals 2R and 4L are at stop so that relays 2RHK and 4LHK are released, and switch lock lever 2WL is in its center position. The lever 2WL is preferably of the push-turn type shown in Letters Patent of the United States No. 2,289,736 to C. S. Snavely and R. H. Zetwo.

To enable a train to enter the main line via switch 2W the central office operator in response to a telephone call from the train crew will move the lever 2WL to the left or right according to the direction the train is to move after entering the single track stretch, and if the entering signals are at stop and the block is unoccupied so that the indication relays are released, movement of the lever 2WL to either of its positions results in the supply of energy to relay 2-4LP to move its contacts to a position corresponding to that of lever 2WL if the lever 2WL and the contacts of relay 2-4LP are out of correspondence.

If lever 2WL is moved to its left-hand position, energy is supplied over back contacts of the various indication relays, contacts 40 and 41 of lever 2WL, and contact 69 of lever 2SIG, to the lower winding of relay 2-4LP. The energy supplied to this winding maintains the relay contacts in their left-hand position, as shown.

If lever 2WL is moved to its right-hand position, energy is supplied over back contacts of the various indication relays, contact 40 of lever 2WL, and contact 43 of lever 4SIG to the upper winding of relay 2-4LP to move the relay contacts to their right-hand position.

During turning movement of the lever 2WL, contacts 86 and 90 are closed, and when contact 87 of lever 2WL and contact 88 of relay 2-4LP are in correspondence, either as a result of movement of the lever into correspondence with the relay contacts or movement of the relay contacts into correspondence with the lever, energy is supplied to relays 2RBK and 4LBK and their contacts pick up to establish stick circuits for the 75 relays and to cause contacts 36 and 35 to interrupt

the circuits of relay 2-4LP and thus prevent a change in the designated traffic direction.

If the contacts of relay 2-4LP are moved as a result of movement of the lever 2WL, the polarity of the energy supplied to the relay 2-4LPS is changed and the relay contacts release. On release of the relay 2-4LPS at this time, its contact 47 does not establish the pick-up circuit for relay 2-4BKSR since this circuit is interrupted by contact 48 of lever 2WL. Accordingly, relay 2-4BKSR remains released and its contact 49 does not establish the relay stick circuit, while its contact 39 does not establish the connection shunting contacts 35 and 36 of relays 4LBK and 2RBK in the circuits of the relay 2-4LP. On release of relay 2-4LPS its contacts 45 and 46 establish pick-up circuits for relays 4LBK and 2RBK to pick up these relays if they are not picked up by energy supplied over other circuits and contacts 35 and 36 of relays 4LBK and 2RBK interrupt the circuits of relay 2-4LP to prevent movement of the relay contacts to change the designated traffic direction.

Momentary closing of front contacts 79 and 71 of lever 2WL during turning of lever 2WL establishes pick-up circuits for the relays 1-2ST and 3-4ST and initiates transmission of control codes to the field stations at both ends of the stretch.

On picking up of the starting relays 3-4ST and 1-2ST their contacts 52 and 53 permit energy to be supplied over the pick-up circuit for relay 2-4LPS as soon as relays 2RBK and 4LBK pick up to close their front contacts 55 and 56 and the office coding unit operates to supply energy to terminal 57. At this time, as explained above, relay 2-4BKSR remains released so its contact 54 in the pick-up circuit for relay 2-4LPS is open, but this contact is shunted by contact 85 of lever 2WL so energy is supplied to relay 2-4LPS, if the relay contacts released, and the contacts of relay 2-4LPS pick up to establish the stick circuit for relay 2-4LPS and contacts 46 and 45 of relay 2-4LPS interrupt the pick-up circuits for relays 2RBK and 4LBK.

If at the time the control codes are transmitted the lever 2WL and the contacts of relay 2-4LP are both in their left-hand positions, energy is supplied to channel 2 over normal polar contact 30 of relay 2-4LP and contact 64 of relay 1-2S during transmission of a control code to the west end of the stretch so that the west end of the stretch is made an exit end. In addition, during transmission of a control code to the west end of the stretch, energy is supplied to channel 4 over the circuit including back contact 74 of relay 4LHK, back contact 75 of relay 2RHK, contact 76 of lever 2WL, contact 77 of lever 2SIG, contact 78 of lever 4SIG, and front contact 80 of relay 1-2S so that, as explained in the above-identified application of H. S. Young, a relay at the left-hand end of the stretch conditions that end of the stretch to be an exit end if it is not so conditioned by the relay governed over channel 2, while the relay governed over channel 4 prevents transmission of a block clear indication code from the west end of the stretch and the next indication code sent from this field station maintains relay 2RBK picked up so that its contact 36 interrupts the circuits of relay 2-4LP and thus prevents movement of the contacts of this relay to change the designated traffic direction.

When control codes are transmitted to the right-hand end of the stretch and the lever 2WL and the contacts of relay 2-4LP are both in their left-hand positions, energy is supplied to chan-

nel 2 over the circuit including back contact 74 of relay 4LHK, back contact 75 of relay 2RHK, contact 76 of lever 2WL, contact 77 of lever 2SIG, contact 78 of lever 4SIG, and front contact 82 of relay 3-4S and this end of the stretch is conditioned to be an exit end. As both ends of the stretch are conditioned to be exit ends the wayside equipment operates to permit the switch 2W to be moved to enable the train on the siding to enter the main track.

If at the time the control codes are transmitted the lever 2WL and the contacts of relay 2-4LP are both in their right-hand positions, energy is not supplied to channel 2 during transmission of a control code to the field station at the left-hand end of the stretch as normal polar contact 30 of relay 2-4LP is open. However, during transmission of a control code to this field station, energy is supplied to channel 4 over the circuit including back contact 74 of relay 4LHK, back contact 75 of relay 2RHK, contact 76 of lever 2WL, contact 77 of lever 2SIG, contact 78 of lever 4SIG, and front contact 80 of relay 1-2S so that the relay at the field station at the left-hand end of the stretch and governed over channel 4 conditions that end of the stretch to be an exit end and also operates to prevent transmission of a block clear indication code from that field station.

When control codes are transmitted to the field station at the right-hand end of the stretch and the contacts of relay 2-4LP are in their right-hand positions, energy is supplied to channel 2 over reverse polar contact 30 of relay 2-4LP and front contact 21 of relay 3-4S and the equipment at this field station conditions this end of the stretch to be an exit end. As both ends of the stretch are conditioned to be exit ends the wayside equipment operates to permit the switch 2W to be moved to enable the train on the siding to enter the main track.

After transmission of control codes to the two ends of the stretch an indication code may be sent from the field station at the right-hand end of the stretch to release relay 4LBK so that its back contact 35 is closed. However, as previously explained, the relay at the field station at the left-hand end of the stretch and controlled over channel 4 prevents the transmission of a block clear indication code from that station and relay 2RBK is certain to remain picked up so that its contact 36 interrupts the circuits for relay 2-4LP to thereby prevent a change in the position of the contacts of relay 2-4LP. If a change in the position of the contacts of relay 2-4LP could occur following unlocking of the switch 2W and movement of a train over this switch into the main track stretch, it might result in putting to stop in front of the train a signal at an intermediate point in the single track stretch with resultant delay to this train and in clearing of the track stretch for other traffic.

This system is arranged to eliminate this possibility by preventing movement of the contacts of relay 2-4LP as the relays 2RBK and 4LBK are picked up as a result of movement of lever 2WL, and the relay 2RBK is thereafter maintained picked up because a block clear indication code cannot be transmitted from the west end of the stretch, while on movement of lever 2WL away from its center position, the relay 2-4BKSR is maintained released so that its contact 39 does not shunt the contacts of relays 2RBK and 4LBK in the circuits of the relay 2-4LP.

After a train has entered the main track stretch 75 over the switch 2W and the switch has been re-

turned to its original position and locked, the operator may convert the end of the stretch behind the train to an entrance end so that the head-block signal at this location may be cleared to permit a following train to enter the stretch.

If the contacts of relay 2-4LP are in their left-hand position, as shown, indicating that the train was to go west after entering the main track, the lever 2WL will be in its left-hand position, and on movement of the lever to its center position contact 76 of the lever 2WL interrupts the circuits for supplying energy to channel 4 during transmission of a control code to the station at the left-hand end of the stretch, and for supplying energy to channel 2 during transmission of a control code to the station at the right-hand end of the stretch.

On this movement of lever 2WL to its center position, the contacts of relay 2-4LP remain in their left-hand position so there is no change in the energy supplied to relay 2-4LPS over its stick circuit and the relay contacts remain picked up. Accordingly, when lever 2WL is moved to its center position and its contact 48 is closed, energy is not supplied to relay 2-4BKSR as contact 47 of relay 2-4LPS is picked up. Relay 2-4BKSR, therefore, remains released and its contact 39 does not shunt the contacts of relays 2RBK and 4LBK in the circuits of relay 2-4LP, and the circuits of relay 2-4LP continue to be controlled by relays 2RBK and 4LBK so that the designated direction of traffic cannot be changed at this time.

During movement of the lever 2WL from its left-hand to its center position, contacts 70 and 71 momentarily establish circuits for the relays 1-2ST and 3-4ST and they pick up to establish stick circuits for themselves and initiate the transmission of control codes to the field stations. In addition, during movement of lever 2WL to its center position, contacts 86 and 90 establish circuits to supply energy to relays 2RBK and 4LBK and they pick up if they are not already picked up.

If lever 4SIG is now moved to its left-hand position, energy will be supplied to channel 5 over normal polar contact 30 of relay 2-4LP, front contact 31 of relay 3-4S and contact 32 of lever 4SIG, during transmission of a control code to the field station at the right-hand end of the stretch, while energy is not supplied to channel 2 during transmission of a control code to this station so the right-hand end of the stretch is converted to an entrance end and the signal control relay is operated to permit clearing of a signal 4L if conditions are proper.

As pointed out above, the circuit for supplying energy to channel 4 during transmission of a control code to the station at the left-hand end of the stretch is interrupted so the equipment at that field station is converted to a normal exit end and block indication codes may be transmitted to the office to show traffic conditions in the stretch.

The equipment operates in a similar manner if the train entering the main track over switch 2W had proceeded to the east and the operator had thereafter wished to clear one of the signals 2R behind the train and a detailed explanation of the operation of the equipment at such times is not deemed necessary.

When the lever 2WL is restored to its normal position and control codes are transmitted while the signal levers are in their stop positions, an end of the stretch is converted from an exit to an entrance end to thereby prepare the stretch

for traffic in the direction designated by relay 2-4LP and the block indication relays 2RBK and 4LBK thereafter function in the normal manner to prevent energization of relay 2-4LP while the stretch is occupied but to permit this relay to be energized to change the designated traffic direction when the stretch is vacated.

Where some forms of wayside signal circuits are employed, occupancy of an entire stretch is indicated at times from one end of the stretch and at other times from the other end of the stretch instead of a portion of the stretch being indicated from one end and the remainder being indicated from the other end. Where this arrangement is employed the block indication relay at the office which is governed from the exit end of the stretch is continuously picked up regardless of traffic conditions in the stretch, while the block indication relay at the office which is governed from the entrance end of the stretch is released or is picked up according as the stretch is vacant or is occupied. Accordingly, where occupancy of the entire stretch is indicated from one end or the other, one or the other of the relays 4LBK or 2RBK is released when the stretch is vacant, but both of these relays are not released at the same time. In these situations the stick circuit for the relay 2-4BKSR should be modified as shown in Fig. 2 so that the contacts 61 and 60 of these relays are connected in series instead of in multiple as shown in Fig. 1. In addition, in these situations, the circuits of relay 2-4LP should be modified as shown in Fig. 3 so that contacts 35 and 36 of relays 4LBK and 2RBK are connected in multiple instead of in series as shown in Fig. 1.

The operation of the equipment when modified as shown in Figs. 2 and 3 is substantially the same as the system shown in Fig. 1 and a detailed explanation of the operation of the equipment is not deemed necessary.

Although we have herein illustrated and described only one form of railway traffic controlling apparatus embodying our invention, together with modifications thereof which we may employ, it is understood that various changes and modifications may be made therein within the scope of the appended claims without departing from the spirit and scope of our invention.

Having thus described our invention, what we claim is:

1. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office including contacts movable between a first and a second position for controlling circuits governing transmission of control codes to said traffic direction relays to cause them to establish traffic in one direction or the other according as said contacts occupy their first or their second position, block indication means at said control office for indicating whether said stretch is occupied or is unoccupied, circuit means for operating said electro-responsive means to change the position of said contacts provided said block indication means indicates the stretch to be unoccupied, an auxiliary relay having contacts movable between a first position in which they permit the block indication means to indicate

19

that the stretch is unoccupied and a second position in which they prevent said block indication means from indicating that the stretch is unoccupied, means operative on movement of the contacts of said electroresponsive means between their two positions to move the contacts of said auxiliary relay to their second position, and means effective when transmission of control codes to the traffic direction relays at both ends of the stretch is initiated for moving the contacts of said auxiliary relay to their first position.

2. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating whether said stretch is occupied or is unoccupied, circuit means for operating said electroresponsive means to change the designated traffic direction provided said block indication means indicates the stretch to be unoccupied, an auxiliary relay having contacts movable between a first position in which they permit the block indication means to indicate that the stretch is unoccupied and a second position in which they prevent said block indication means from indicating that the stretch is unoccupied, means responsive to operation of said electroresponsive means to change the designated traffic direction for moving the contacts of said auxiliary relay to their second position, and means effective when transmission of control codes to the traffic direction relays at both ends of the stretch is initiated for moving the contacts of said auxiliary relay to their first position.

3. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating whether said stretch is occupied or is unoccupied, an auxiliary relay having contacts movable between a first position in which they permit the block indication means to indicate that the stretch is unoccupied and a second position in which they prevent said block indication means from indicating that the stretch is unoccupied, a block indication repeater relay having contacts which occupy a second position when the auxiliary relay contacts are in their second position and which when in their second position move to their first position when the block indication means indicates that the stretch is unoccupied, circuit means for operating said electroresponsive means to change

20

the designated traffic direction provided said block indication means indicates that the stretch is unoccupied or the contacts of said block indication repeater relay are in their second position, means responsive to operation of said electroresponsive means to change the designated traffic direction for moving the contacts of said auxiliary relay to their second position, and means effective when transmission of control codes to the traffic direction relays at both ends of the stretch is initiated for moving the contacts of said auxiliary relay to their first position.

4. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, a polarized relay at a control office having contacts governing transmission of control codes to said traffic direction relays to cause them to establish traffic in one direction or the other according as the contacts of said polarized relay occupy their normal or their reverse position, block indication means at said control office for indicating whether said stretch is occupied or is unoccupied, circuit means for operating the contacts of said polarized relay between their two positions provided said block indication means indicates that the stretch is unoccupied, an auxiliary relay having contacts movable between a first position in which they permit the block indication means to indicate that the stretch is unoccupied and a second position in which they prevent said block indication means from indicating that the stretch is unoccupied, means operative on movement of the contacts of said polarized relays between their two positions to cause the contacts of said auxiliary relay to occupy their second position, and means effective when transmission of control codes to the traffic direction relays at both ends of the stretch is initiated for causing the contacts of said auxiliary relay to occupy their first position.

5. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, circuit means for operating said electroresponsive means to change the designated traffic direction, an auxiliary relay having contacts movable between a first and a second position, a starting relay for each end of the stretch adapted when actuated to initiate transmission of a control code to the associated end of the stretch, a starting button for each starting relay, each starting button controlling a circuit for actuating the associated starting relay, means responsive to operation of said electroresponsive means to change the designated traffic direction for causing the contacts of said auxiliary relay to occupy their second position, means effective when the contacts of said auxiliary relay are in their second position to establish for the starting relay for each end of the stretch a cir-

21

cuit controlled by the starting button associated with the starting relay for the other end of the stretch, and means effective when the starting relays for both ends of the stretch are actuated to cause the contacts of said auxiliary relay to occupy their first position.

6. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating whether said stretch is occupied or is unoccupied, an auxiliary relay having contacts movable between a first position in which they permit the block indication means to indicate that the stretch is unoccupied and a second position in which they prevent said block indication means from indicating that the stretch is unoccupied, a block indication repeater relay having contacts which occupy a second position when the auxiliary relay contacts are in their second position and which when in their second position move to their first position when the block indication means indicates that the stretch is unoccupied, circuit means for operating said electroresponsive means to change the designated traffic direction provided said block indication means indicates that the stretch is unoccupied or the contacts of said block indication repeater relay are in their second position, a starting relay for each end of the stretch adapted when actuated to initiate transmission of a control code to the associated end of the stretch, a starting button for each starting relay, each starting button controlling a circuit for actuating the associated starting relay and also controlling a circuit for actuating the starting relay for the other end of the stretch provided the contacts of said block indication repeater relay are in their second position, means responsive to operation of said electroresponsive means to change the designated traffic direction for causing the contacts of said auxiliary relay to occupy their second position, and means effective when the starting relays for both ends of the stretch are actuated to cause the contacts of said auxiliary relay to occupy their first position.

7. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, circuit means for operating said electroresponsive means to change the designated traffic direction, a starting relay for each end of the stretch adapted when actuated to initiate transmission of a control code to the associated end of the stretch, a neutral auxiliary relay hav-

22

ing a pick-up circuit established when the starting relays for both ends of the stretch are actuated and having a stick circuit including its own front contact, the pick-up and stick circuits for said auxiliary relay being governed by said electroresponsive means so that the energy supplied to said auxiliary relay over said circuits develops flux of one polarity or the other in the relay core according as the electroresponsive means designates traffic in one direction or the other, and a starting button for each starting relay, each starting button controlling a circuit for actuating the associated starting relay and also controlling a circuit for actuating the starting relay for the other end of the stretch provided said auxiliary relay is released.

8. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, circuit means for operating said electroresponsive means to change the designated traffic direction, a neutral auxiliary relay having a pick-up circuit established when transmission of control codes to both ends of the stretch is initiated and having a stick circuit including its own front contact, the pick-up and stick circuits for said auxiliary relay being governed by said electroresponsive means so that the energy supplied to said auxiliary relay over said circuits develops flux of one polarity or the other in the relay according as the electroresponsive means designates traffic in one direction or the other, and a starting button for each end of the stretch, each starting button controlling a circuit for initiating transmission of a control code to the associated end of the track stretch and also controlling a circuit for initiating transmission of a control code to the other end of the stretch provided said auxiliary relay is released.

50 9. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating whether said stretch is occupied or is unoccupied, a neutral auxiliary relay having contacts effective when picked up to permit the block indication means to indicate that the stretch is unoccupied and effective when released to prevent said block indication means from indicating that the stretch is unoccupied, a repeater relay having contacts which occupy a first position when the auxiliary relay contacts are released and which when in their first position move to a second position when the block indication means indicates that the stretch is

23

unoccupied, circuit means for operating said electroresponsive means to change the designated traffic direction provided said block indication means indicates that the stretch is unoccupied or the contacts of said repeater relay are in their first position, a pick-up circuit for said auxiliary relay established when transmission of control codes to both ends of the stretch is initiated, a stick circuit for said auxiliary relay including its own front contact, the pick-up and stick circuits for said auxiliary relay being governed by said electroresponsive means so that the energy supplied to said auxiliary relay develops flux of one polarity or the other in the relay according as said electroresponsive means designates traffic in one direction or the other, and a starting button for each end of the stretch, each starting button controlling a circuit for initiating transmission of a control code to the associated end of the stretch and also controlling a circuit for initiating transmission of a control code to the other end of the stretch provided said repeater relay contacts are in their first position.

10. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, circuit means for operating said electroresponsive means to change the designated traffic direction, an auxiliary relay associated with said electroresponsive means and governed so that its contacts are moved to a first position whenever the direction of traffic designated by said electroresponsive means is changed, a starting button for each end of the stretch, each starting button controlling a circuit for initiating transmission of a control code to the associated end of the stretch and also controlling a circuit for initiating transmission of a control code to the other end of the stretch provided the contacts of said auxiliary relay are in their first position, and means effective when transmission of control codes to both ends of the stretch is initiated for moving the contacts of said auxiliary relay from their first to their second position.

11. In direction selecting means for a stretch of railway track equipped with a signaling system governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating whether said stretch is occupied or is unoccupied, an auxiliary relay associated with said electroresponsive means and governed so that its contacts are moved to a first position whenever the direction of traffic design-

24

nated by said electroresponsive means is changed, the auxiliary relay contacts being effective when in their first position to prevent the block indication means from indicating that the stretch is unoccupied and being movable to a second position in which they permit the block indication means to indicate that the stretch is unoccupied, circuit means for operating said electroresponsive means to change the designated traffic direction provided said block indication means indicates that the stretch is unoccupied, a starting button for each end of the stretch, each starting button controlling a circuit for initiating transmission of a control code to the associated end of the stretch and also controlling a circuit for initiating transmission of a control code to the other end of the stretch provided the contacts of said auxiliary relay are in their first position, and means effective when transmission of control codes to both ends of the stretch is initiated for moving the contacts of said auxiliary relay from their first to their second position.

12. In direction selecting means for a stretch of railway track equipped with a signaling system including entering signals at opposite ends of the stretch which are governed by code controlled relays so that at times the signal at one end of the stretch may be cleared and at other times the signal at the other end of the stretch may be cleared, in combination, electroresponsive means at a control office capable of designating traffic in one direction or the other and controlling circuits governing transmission of control codes to said signal control relays to cause them to permit clearing of the signal governing traffic in the direction designated by said electroresponsive means, an auxiliary relay associated with said electroresponsive means and governed so that its contacts are moved to a first position whenever the direction of traffic designated by said electroresponsive means is changed, a starting button for each end of the stretch, each starting button controlling a circuit for initiating transmission of a control code to the associated end of the stretch and also controlling a circuit for initiating transmission of a control code to the other end of the stretch provided the contacts of said auxiliary relay are in their first position, and means effective when transmission of control codes to both ends of the stretch is initiated for moving the contacts of said auxiliary relay from their first to their second position.

13. In direction selecting means for a stretch of railway track equipped with a signalling system governed jointly by code controlled relays at opposite ends of the stretch, the equipment at each end of the stretch being capable of conditioning the associated end of the stretch to be an exit or an entrance end, in combination, electroresponsive means at a control office capable of designating traffic in one direction or the other and controlling circuits governing transmission of control codes to said code controlled relays to cause them to establish traffic in the direction designated by said electroresponsive means, block indication means at said control office for indicating whether said stretch is occupied or is unoccupied, an auxiliary relay having contacts movable between a first position in which they permit the block indication means to indicate that the stretch is unoccupied and a second position in which they prevent said block indication means from indicating that the stretch is unoccupied, means for governing said auxiliary relay to cause

its contacts to move to their second position whenever the direction of traffic designated by said electroresponsive means is changed, a switch lock control member having a normal position from which it is movable to an unlocked position in which it controls the circuits governing transmission of control codes to said code controlled relays to cause the relays at both ends of the stretch to condition the associated end of the stretch to be an exit end, a repeater relay having contacts which are moved to a second position when the auxiliary relay contacts are in their second position provided said switch lock member is in its normal position and which when in their second position move to their first position when the block indication means indicates that the stretch is unoccupied, circuit means for operating said electroresponsive means to change the designated traffic direction provided said block indication means indicates that the stretch is unoccupied or the contacts of said repeater relay are in their second position, and means effective when transmission of control codes to both ends of the stretch is initiated for moving the contacts of said auxiliary relay to their first position.

14. In direction selecting means for a stretch of railway track equipped with a signaling system governed jointly by code controlled relays at opposite ends of the stretch, the equipment at each end of the stretch being capable of conditioning the associated end of the stretch to be an exit or an entrance end, in combination, electroresponsive means at a control office capable of designating traffic in one direction or the other and controlling circuits governing transmission of control codes to said code controlled relays to cause them to establish traffic in the direction designated by said electroresponsive means, block indication means at said control office for indicating whether said stretch is occupied or is unoccupied, an auxiliary relay having contacts movable between a first position in which they permit the block indication means to indicate that the stretch is unoccupied and a second position in which they prevent said block indication means from indicating that the stretch is unoccupied, means for governing said auxiliary relay to cause its contacts to move to their second position whenever the direction of traffic designated by said electroresponsive means is changed, a switch lock control member having a normal position from which it is movable in either direction to positions in which it controls the circuits governing transmission of control codes to said code controlled relays to cause the relays at both ends of the stretch to condition the associated end of the stretch to be an exit end and in which if said block indication means indicates that the stretch is unoccupied said member governs circuit means to cause said electroresponsive means to designate traffic in the direction determined by the direction in which said switch lock control member is moved from its normal position, a repeater relay having contacts which are moved to a second position when the auxiliary relay contacts are in their second position provided said switch lock member is in its normal position and which when in their second position move to their first position when the block indication means indicates that the stretch is unoccupied, other circuit means for operating said electroresponsive means to change the designated traffic direction provided said block indication means indicates that the stretch is unoccupied or the contacts of said repeater relay are in their second position, and

means effective when transmission of control codes to both ends of the stretch is initiated for moving the contacts of said auxiliary relay to their first position.

15. In direction selection means for a stretch of railroad track having at one end a first detector section and having at the other end a second detector section, said track stretch being equipped with signalling apparatus governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating occupancy of said stretch, detector section indication means at said control office for each of said detector sections for indicating occupancy thereof, a block indication repeater relay having contacts which are moved from a first to a second position on operation of said electroresponsive means to change the designated traffic direction and which are moved from their second to their first position when said block indication means indicates that said stretch is unoccupied or said detector section indication means indicates that a detector section is occupied, and circuit means for operating said electroresponsive means to change the designated traffic direction provided said block indication means indicates that the stretch is unoccupied or the contacts of said repeater relay are in their second position.

16. In direction selection means for a stretch of railroad track having at one end a first detector section and having at the other end a second detector section, said track stretch being equipped with signaling apparatus governed jointly by code controlled traffic direction relays at opposite ends of the stretch so that at times the stretch is conditioned for traffic in one direction and at other times is conditioned for traffic in the other direction, in combination, electroresponsive means at a control office capable of designating traffic in one direction or the other and controlling circuits governing transmission of control codes to said traffic direction relays to cause them to establish traffic in the direction designated by said electroresponsive means, block indication means at said control office for indicating occupancy of said stretch, detector section indications means at said control office for each of said detector sections for indicating occupancy thereof, a block indication repeater relay having contacts which are moved from a first to a second position on operation of said electroresponsive means to change the designated traffic direction and which are moved from their second to their first position when said block indication means indicates that said stretch is unoccupied or said detector section indication means indicates that a detector section is occupied, and circuit means for operating said electroresponsive means to change the designated traffic direction provided the detector section indication means shows the detector sections to be unoccupied and also provided said block indication means indicates that the block is unoccupied or the contacts of said repeater relay are in their second position.

17. Direction selecting apparatus for controlling traffic movements over a stretch of single track railway equipped with a reversible signaling system, said track stretch having at one end a first detector section and having at the other end a second detector section, electroresponsive means at a control office capable of designating traffic in one direction or the other, a code communication system for transmitting manually initiated control codes reflecting the condition of said electroresponsive means to stations at the ends of said stretch to control said signaling system and for automatically transmitting indication codes from said stations reflecting the condition of occupancy of the stretch to control block indication relays at the office and reflecting the condition of occupancy of said detector sections to control detector section indication relays at the office, a repeater relay at said control office, means effective when said electroresponsive means is operated to change the designated traffic

20

direction for moving the contacts of said repeater relay from their first to their second position and for operating said block indication relays to the positions which they assume in response to received codes indicating that the stretch is occupied, means for moving the contacts of said repeater relay from their second to their first position when indication codes are received to operate the block indication relays to the positions which they assume when the stretch is unoccupied or when an indication code is received that one of said detector sections is occupied, and circuit means for operating said electroresponsive means to change the designated direction of traffic provided said block indication relays are in the position which they assume in response to received codes indicating that the stretch is unoccupied or the contacts of said repeater relay are in their second position.
